MANICURIST'S HAND REST

Catherine Goergen, 1064 Elkgrove Ave.,
Venice, Calif. 90291

Filed Aug. 1, 1974, Ser. No. 493,678

Term of patent 14 years

Int. Cl. D28—03

U.S. Cl. D86—10 C

Fig. 1.

Fig. 4.

Fig. 2.

Fig. 3.

Fig. 5.

FIG. 1 is a top plan view of a manicurist's hand rest, showing my new design;

FIG. 2 is a side elevational view thereof;

FIG. 3 is a bottom plan view thereof;

FIG. 4 is a front elevational view thereof; and

FIG. 5 is a rear elevational view thereof.

The hand rest is symmetrical about a vertical longitudinal plane.

I claim:

The ornamental design for a manicurist's hand rest, substantially as shown and described.
